Filed Aug. 14, 1969, Ser. No. 18,679

Term of patent 14 years

Int. Cl. D6—01

U.S. Cl. D33—26

FIG. 1 is a perspective view of a combination cup dispenser and toothbrush holder embodying my new design;

FIG. 2 is a side elevational view thereof;

FIG. 3 is a perspective view of a modified form of the combination cup dispenser and toothbrush holder shown in FIG. 1;

FIG. 4 is a side elevational view of FIG. 3;

FIG. 5 is a top plan view of FIG. 3.

The broken line representation of a cup and a support bracket in FIGS. 1 through 4, is for purposes of illustration only.

I claim:

The ornamental design for a combination cup dispenser and toothbrush holder, as shown and described.
